UNITED STATES PATENT OFFICE

ARTHUR T. BATEMAN AND ANDREW IRVINE, OF DETROIT, MICHIGAN, ASSIGNEES TO
BOHN ALUMINUM & BRASS CORPORATION, OF DETROIT, MICHIGAN, A CORPORA-
TION OF MICHIGAN

MOLD

Application filed July 30, 1928. Serial No. 296,379.

The invention relates to molds and refers more particularly to molds for use in casting hollow articles. One of the objects of the invention is to provide an improved 5 permanent mold, which is so constructed that it may be readily operated at a rate of speed to maintain a sufficiently high temperature to produce good castings. Another object is to provide an improved mechanism 10 for actuating the core. Further objects of the invention reside in the novel features of construction and combinations and arrangements of parts as more fully hereinafter set forth.

15 In the drawings:—

Figure 1 is a plan view of the mold, embodying our invention;

Figure 2 is an end view partly in section thereof;

20 Figure 3 is a vertical sectional view thereof;

Figure 4 is a similar view of a modified construction of core actuating mechanism;

Figure 5 is a cross section on the line 5—5 25 of Figure 4.

The mold embodying the invention has been developed in casting motor casings for vacuum cleaners from metal of relatively high crystallization shrinkage and relative- 30 ly low fusing point, such as aluminum and its alloys, and, as shown, this mold has the permanent metal mold sections 1 and 2, which are pivotally connected at one end by the vertical pin 3 and which are adapted to 35 be suitably connected at the other end when in closed or casting position, at which time they cooperate to form the downwardly opening cup-shaped mold cavity 4. The mold sections rest upon the support 5, which

40 is in the nature of a table and in which the pin 3 is mounted. The casting which is formed in this mold has the opening 6 in its closed end and the external flat face 7 in its side adjacent the opening 6. The casting also has the opening 8 in its side 45 in alignment with the flat face 7 and adjacent its open end.

9 is a permanent metal main core which is adapted to be inserted upwardly into the 50 mold cavity and to be withdrawn down-

wardly therefrom. 10 is a second permanent metal core which is adapted to be inserted downwardly into the mold cavity and withdrawn upwardly therefrom. This second core has a portion 10' which is engageable with the core 9 to form the opening 6 and a flat faced portion 10² which is adapted to form the flat face 7. 11 is a third permanent metal core which is horizontally reciprocable into and out of the mold cavity and is adapted to form the opening 8. This third core is suitably guided to move in a rectilinear path by being made to fit in the guideway 12 formed in the upper face of the support 5. 13 is a horizontally movable lever pivotally connected at 14 to the support 5 and pivotally connected intermediate its ends by the pin 15 to the core 11.

Since considerable force is often required to withdraw the main core 9 after the casting 70 has been poured, we have provided toggle linkage for actuating the core, and since it is essential that the core be guided to move in a rectilinear path, we have provided means for guiding the core to move in a 75 rectilinear path and we have arranged the connection between the toggle linkage and the core to permit this movement. In detail, 16 is a bushing encircling and guiding the core, this bushing being rigidly secured

80 to the support 5 and preferably extending upwardly therethrough to form a pilot or stop in the nature of an annular shoulder for locating the mold sections 1 and 2 in their closed or casting position. 17 are suitable keys secured to the core at diametrically opposite sides and adapted to slidably engage in keyways 18 extending longitudinally in the bushing. 19 is a link pivotally connected at 20 to the lug 21 upon the bushing 85 16, and 22 is a lever pivotally connected at one end to the lower end of the link 19 by the pin 23, this lever extending preferably at right angles to the line connecting the keys 17 and being pivotally connected at 24 to the core. The other end of the lever is pivotally connected to the toggle linkage 90

25, which comprises the toggle links 26 and 27 pivotally connected together at 28. The lower end of the toggle link 26 is pivotally 95 connected at 29 to the pin 15 and the upper end of the toggle link 27 is pivotally 100 connected at 30 to the pin 14. The lever 22 is pivotally connected at 31 to the pin 14.

connected by the pin 29 to the lever 22. The toggle link 27 is pivotally connected by the pin 30 to the bracket 31 rigidly secured to the support 5. 32 is a hand lever connected to the toggle link 27 and extending at an angle therefrom for actuating the same. The arrangement is such that when the main core is in casting position, as determined by the collar 33 which is adjustably threaded 10 upon the main core and is adapted to abut the lower end of the bushing 16, the common pivot 28 of the toggle links extends adjacent to the plane extending through the axes of their other pivots 29, and 30, and 15 the handle is inclined toward the mold sections 1 and 2, thereby automatically holding the main core in its casting position through both the toggle levers and the weight of the hand lever. The arrangement also provides 20 great leverage for withdrawing the main core from the casting and furthermore provides the greatest leverage during the initial portion of the withdrawal movement of the main core.

25 The lever 22 is resilient to a sufficient extent to flex, and the movement of the hand lever 32 and toggle linkage 25 in a direction to raise the main core 9 to casting position is such that the lever is flexed after the 30 collar 33 abuts the bushing 16, thereby assuring proper positioning of the main core in its casting position.

In the modifications shown in Figures 4 and 5, the mechanism for actuating the 35 main core of the mold differs from the corresponding mechanism shown in Figures 1, 2 and 3, mainly by providing an adjustable connection between the lever 34, which is pivotally connected to the main core, and the toggle linkage 35. This toggle linkage 40 comprises the toggle links 36 and 37, which are pivotally connected to each other at 38. The toggle link 36 is U-shaped and is connected to the lever 34 by means of the eye-bolt 39 and the pin 40, the eye-bolt extending transversely through the base 41 of the toggle link and being adjustably secured thereto by means of the nuts 42 threaded upon the shank of the eye-bolt and abutting 45 opposite sides of the base.

50 What we claim as our invention is:

1. In a mold, the combination with horizontally movable pivotal permanent sections adapted to cooperate to form a vertically 55 extending mold cavity, of a vertically movable permanent core adapted to be positioned in the mold cavity, and guiding means for said core forming a stop for said sections.

2. In a mold, the combination with horizontally 60 movable pivotal permanent sections adapted to cooperate to form a vertically extending mold cavity, of a horizontally 65 movable permanent core adapted to be positioned in the mold cavity, vertically movable cores adapted to be positioned in the

mold cavity and contact with each other, and guiding means for one of said cores forming a stop for said sections.

3. The combination with a support and a permanent mold upon the support having a mold cavity, of a permanent core adapted to be positioned within the mold cavity and to be withdrawn therefrom, a pivotal link, a lever pivotally connected to said link and also connected to the core, and toggle linkage pivotally connected to said lever for swinging the same to actuate the core, said link being adapted to swing to provide for rectilinear movement of the core. 70 75

4. The combination with a support and a permanent mold upon the support having a downwardly opening mold cavity, of a permanent core adapted to be positioned within the mold cavity and to be withdrawn therefrom, a member secured to the support and forming a bushing for the core, a link pivotally connected to and depending from the member, a lever pivotally connected to the lower end of the first mentioned link and connected to the core, and toggle linkage 80 85 connected to the support and lever for swinging the latter to actuate the core. 90

5. The combination with a permanent mold having a mold cavity, of a permanent core adapted to be positioned within the mold cavity and to be withdrawn therefrom, toggle linkage, a lever connected to said core and toggle linkage for actuating the former from the latter, and means for adjustably connecting said lever to said toggle linkage. 95 100

6. The combination with a permanent mold having a mold cavity, of a permanent core adapted to be positioned within the mold cavity and to be withdrawn therefrom, a pivotal link, toggle linkage, a lever pivotally connected to said link and core, and means for adjustably connecting said lever to said toggle linkage. 105

7. The combination with a mold having a mold cavity, of a core adapted to be positioned within the mold cavity and to be withdrawn therefrom, and means for actuating the core including toggle linkage and a hand lever connected thereto and adapted by its weight to automatically hold the core 110 115 within the mold cavity.

In testimony whereof we affix our signatures.

ARTHUR T. BATEMAN.
